UNITED STATES PATENT OFFICE

2,419,802

MOTOR MURAL COMPRISING A CANVAS
MOVED ALONG A WALL FROM ONE SPOOL
TO ANOTHER

Mark Van Horne, Rochester, N. Y.

Application April 19, 1944, Serial No. 531,796

2 Claims. (Cl. 40—31)

1

This invention relates to an apparatus for mounting murals upon a wall of a room and it is one object of the invention to provide an apparatus whereby a mural of extended length may be mounted against a wall of a room and portions of the mural progressively moved into position for display by winding the mural from one roller onto another at the opposite side of a wall from the first roller.

Another object of the invention is to provide an apparatus wherein the rollers carrying the portions of the mural not on display will be hidden and thus not detract from the appearance of the room in which the mural is installed.

Another object of the invention is to provide an apparatus of this character wherein the rollers are driven from electric motors and thus permit the elongated strip of canvas or the like bearing the mural to be easily shifted when so desired.

Another object of the invention is to provide guides for upper and lower edges of the canvas bearing the mural and thus hold the canvas flat against a wall and prevent wrinkles from being formed therein.

Another object of the invention is to provide improved means for connecting ends of the guides with cabinets in which the rollers are mounted, the cabinets having doors which are normally closed but may be opened when oiling or repairs to the motors are necessary.

Another object of the invention is to provide an apparatus which may be very easily installed in a wall either during building of a house or at a later date.

Another object of the invention is to provide an apparatus of this character which is easy to install, efficient in operation and not liable to get out of order.

The invention is illustrated in the accompanying drawings wherein:

Figure 1 is a view in elevation showing the improved motor mural installed in a room.

Figure 2 is a horizontal sectional view taken along line 2—2 of Figure 1.

Figure 3 is a fragmentary view looking at the opposite face of the wall from that shown in Figure 1.

Figure 4 is a sectional view taken vertically thru Figure 1 upon line 4—4.

Figure 5 is a sectional view taken horizontally through an apparatus of modified construction intended to be installed after erection of a building.

2

Figure 6 is a view similar to Figure 5 showing a modified construction.

Figure 7 is a view showing modified construction of guides for the mural.

5 Figure 8 is a fragmentary sectional view showing the manner in which ends of guides are mounted in the roller cabinets.

Figure 9 is a sectional view taken vertically through Figure 8 along line 9—9.

10 Figure 10 is a horizontal sectional view taken along line 10—10 of Figure 8.

Figure 11 is a sectional view taken along line 11—11 of Figure 7.

15 Figure 12 is a fragmentary sectional view taken above line 12—12 of Figure 7.

Figure 13 is a wiring diagram for the motors.

The mural constituting the subject matter of this invention may be scenery, pictures of interesting places or objects, maps, charts, or the like which it is desired to selectively display against a wall of a room such as a living room, library, school room or other room where people gather for pleasure, study, or instruction.

In Figures 1, 2, 3 and 4 the motor mural has been shown mounted directly against the wall 1 at an end of a room which serves as a backing for the strip 2 of canvas or other suitable material upon which the mural is painted. The strip of canvas may be of any desired length and the

30 surface thereof exposed in the room may be painted with scenery, portraits, panoramas, or bear charts, maps, or the like according to whether it serves as a decoration, or for use in a school room. If so desired wall paper may

35 be applied to the exposed surface of the strip in series following one another along the strip and by shifting the strip longitudinally selectively brought into view. The strip may also bear tapestries or other decorative or instructive objects.

40 The strip or apron should remain flat and unwrinkled and in order to do so there have been provided reinforcements 3 consisting of thick tapes or ropes which are adhesively secured to the apron.

45 The canvas strip or apron passes through openings 4 in the wall or backing 1 and wound upon spools 5 rotatably mounted by bearing brackets 6 which project rearwardly from the wall above and below the slots or openings 4, and from an

50 inspection of Figures 2 and 3 it will be seen that turning the spools the mural may be wound from one spool onto the other and a desired portion of the mural brought into position between the spools for display within a frame formed by metal strips 7 and 8 secured against the wall and ex-

tending along the slots and between upper and lower ends of the slots. The strips 7 conceal the slots and are curved transversely, as shown in Figure 2, so that the mural may pass freely through the slots about guide rollers 9 in the slots and strips 8 overlap upper and lower edges of the mural to hide these edges and guide movement of the mural between the slots as well as holding the mural flat against the wall or backing. End portions of the wall and the portion thereof below the frame may be ornamented, as shown at 9, to blend in with the frame and provide an attractive setting for the mural. If the frame occupies a sufficient area of the wall the ornamentation 9 may be omitted.

The spools 5 are to be turned in order to wind the mural or apron from one spool to the other and in order to do so there have been provided electric motors 10 mounted against the rear face of the wall or backing with their shafts projecting downwardly and carrying pulley wheels 11. Larger pulley wheels 12 are mounted upon lower ends of the shafts of the spools 5 and about the pulley wheels 11 and 12 are trained belts 13 by means of which rotary motion is transmitted from the motors to the spools. The motors are controlled by a switch 14, and referring to Figure 12 it will be seen that the circuit for the motors is a three-way system and that by actuating the switch the motors may be individually set in motion. Therefore one motor may be energized to rotate the companion spool and the mural wound upon this spool while it is unwound from the other spool. The inactive motor exerts a drag upon the spool from which the mural or apron is unwound causing the mural to be held smooth against the wall. There has therefore been provided a motor operated mural which will serve very effectively as a changeable decoration for a wall of a room or as a carrier for a series of maps, charts, instructions, or the like in a class room of a school.

In Figures 5 and 6 there has been illustrated an embodiment of the invention wherein the mural is installed in a room as an accessory and instead of having the wall serve as a backing through which the mural passes there has been provided a backing 15 which is mounted flat against the wall in any desired manner. Housings 16 are disposed vertically at opposite ends of the backing and project forwardly therefrom. The spools 17 and their motors 18 are mounted in the housings or cabinets 16 and against inner side walls of the cabinets are mounted guide rollers 19 for directing the mural or apron 20 through slots 21 which may be formed close to the backing as shown in Figure 6 or near outer edges of the side walls 5. Doors 22 are provided at the fronts of the cabinets so that access may be had to the motors and the spools for oiling or repairing the motors or removing the spools when it is desired to substitute another mural in place of one which has been in use.

In order to guide movement of the mural between the cabinets and support the portion on display guides 23 formed as shown in Figures 9 through 11 may be used. These guides are formed of channel metal and each has main sections 24 and an intermediate section 25. The intermediate section 25 has inwardly extending flanges 26 along lower edges of its side walls to engage under side walls of the main sections

and hold the sections in alignment with each other. Outer ends of the main sections have their side walls formed with tongues 27 which extend into brackets 28 mounted in the cabinets at ends of the slots 21 and are interengaged with tongues 29 cut vertically from the sides of the brackets. By this arrangement the cabinets may be disposed at opposite ends of the wall of a room and the upper and lower guides 23 set in place and adjusted to the length of the wall with their ends fitted within the brackets and supported by the tongues 29. Slots 30 at inner ends of the brackets permit passage of the mural through the brackets. There have also been provided vertical bracing bars or strips 31 which extend between the upper and lower guides and have their ends bent to form hooks 32 which engage about the main sections of the guides. While two braces 31 have been shown in Figure 7 it will be understood as many may be provided as found necessary to hold the guides parallel and prevent sagging.

Having thus described the invention, what is claimed is:

1. A motor mural for use in conjunction with the walls of a room comprising a backing positioned on said wall and formed with slots near its ends, spools rotatably mounted adjacent said slots, an apron having end portions wound upon said spools and a portion between the spools covering the front face of said backing and passing through said slots, rollers engaged by said apron and directing the apron through the slots, a frame having end strips concealing the slots and the rollers and upper and lower strips overlapping upper and lower edge portions of said apron between the slots, and motors for individually driving said spools whereby one spool may be power driven to wind the apron thereon from the other spool.
2. A motor mural for use in conjunction with the walls of a room comprising a backing positioned on said wall formed with vertical slots near its ends, spools rotatably mounted in vertical position back of said backing and located adjacent the slots, guide rollers rotatably mounted in said slots, an apron having end portions wound upon said spools with a portion between the spools covering the front face of said backing and passing through said slots in engagement with said guide rollers, a frame having end portions concealing the slots and the rollers and upper and lower portions overlapping and concealing upper and lower edges of the apron between said slots and holding the apron close to the front face of the backing, motors companion to said spools, means for transmitting rotation from said motors to the companion spools, and means for individually operating said motors whereby one spool may be turned to wind the apron thereon from the other spool.
